UNITED STATES PATENT OFFICE.

WILLIAM A. F. MACCALLUM, OF PHILADELPHIA, PENNSYLVANIA.

GOLF ACCESSORY.

Application filed October 31, 1924. Serial No. 746,949.

To all whom it may concern:

Be it known that I, WILLIAM A. F. MACCALLUM, a citizen of the United States, residing at Philadelphia, in the county of Philadelphia and State of Pennsylvania, have invented a certain new and useful Golf Accessory, of which the following is a specification.

This invention, generally stated, relates to an amusement apparatus and has more specific relation to a device to aid in the perfection of golf strokes or swings.

The leading object of the present invention resides in the provision of a simple, efficient, and comparatively inexpensive device of the character stated which may be used indoors or out-of-doors to aid a golfer in perfecting his or her golf swings or strokes.

20 A further object of the present invention resides in the provision of a device of the character stated in which the target after being hit is automatically reset.

25 A further object of the present invention resides in the provision of a target symbolic of a golf ball made up of a plurality of relatively pliable strips of material secured together and pivotally mounted upon a base symbolic of a teeing ground. Other and 30 further objects reside in the provision of general details of construction and arrangement of parts for attaining the results sought by the foregoing objects.

35 The invention consists of the novel construction hereinafter described and finally claimed.

The nature, characteristic features and scope of the invention will be more fully understood from the following description 40 taken in connection with the accompanying drawings forming part hereof, and in which:

Fig. 1, is a top or plan view of a device embodying the invention.

45 Fig. 2, is a view of the underside thereof, and

Fig. 3, is a view in longitudinal section taken upon the line 3—3 of Fig. 1.

For the purpose of illustrating my invention I have shown in the accompanying drawings one form thereof which is at present preferred by me, since the same has been found in practice to give satisfactory and reliable results, although it is to be understood that the various instrumentalities

of which my invention consists can be variously arranged and organized and that my invention is not limited to the precise arrangement and organization of the instrumentalities as herein shown and described.

Referring specifically to the drawings there is disclosed a base preferably of metal in which case it is molded or cast to the general configuration shown. In practice this base is elongated in form and is painted green to symbolize a teeing ground. The forward portion of the base which is designated 1 is elevated and is provided with an elongated opening 2 arranged centrally of the forward portion of the base. This elongated opening 2 is provided upon opposite sides with legs 3 and in advance of the legs 3 is a stop 4 which stop is located at the bottom of the base, the purpose of which will presently appear. Extending from the elevated front portion of the base rearwardly is the inclined portion 5, it being understood that the base line of the base is flat in order that the same may be positioned upon the floor or ground. Apertures 6 are provided in the base so that the same may be secured or nailed to position in order to steady the base. The under side of the inclined portion 5 is slotted at 7 for a purpose to presently appear. The base may be cupped out upon its bottom as at 8 in order to lighten construction. The legs 3 are laterally apertured for the reception of a pin 9 upon which is loosely mounted a member symbolic of a golf ball. This member is of laminated structure, and consists of a plurality of vertically disposed strips 10 of relatively pliable material. In practice good results have been obtained by employing strips of raw hide and securing the strips together under compression by means of belt glue. The strips of material so secured together have preferably fitted therearound a metal casing 11 and laterally disposed pins 12 are employed for securing the casing with respect to the strips 10. The rear and lower portion of the above described member is centrally grooved as at 13 for a purpose to presently appear. The rear face of the strips 10 have delineated thereon as by white paint a representation of a golf ball indicated at 14 in Fig. 1 and which may be of either dimple or mesh representation. Loosely passing through the pivotal member at an inclination, as shown in Fig. 3, is a

link 15 the free ends of which are soldered to a washer 16. Connecting that end of link 15 which projects through the rear portion of the pivotal member and a coil spring 17 is 5 a link 18, the coil spring being secured as at 19 to the underside of the base and being accommodated within slot 7. As the pivotal member moves in the direction of the arrow in Fig. 3 about the rod 19 the grooved portion 13 thereof accommodates the link 18 and during the same movement the spring 17 is confined within slot 7. The pivotal member is limited in its forward movement by the previously described stop 4. The inclined portion 5 has delineated thereon a 15 pair of golf clubs 20 with the heads 21 in opposed relation at the rear of the base and with the shafts of the clubs extending forwardly in diverging relation. 20 The clubs serve the purpose of assisting a player to guide his or her clubs for impact with the pivotal member. To use the above described device the player assumes a position in front of the device and takes his or 25 her golf club, either driver, iron, or putter, and makes natural swings or strokes with the result that impact of the club against the movable member causes it to move forward against stop 4 thereby permitting player to 30 finish or follow through in a natural and well understood manner in golf. The spring 17 causes the movable member to automatically reset itself. By a device of the kind above described a golfer may either indoors 35 or out-of-doors practice in a natural manner golf strokes or swings and as soon as the pivotal member automatically resets itself the annoyance of re-teeing balls is overcome although the player has all the other advantages derived by swinging at a ball. The 40 spring 17 exerts sufficient tension upon the pivotal member so that a player strikes the movable member just as hard as he would a golf ball so that the device in addition to 45 being a convenient form of amusement device also provides more or less exercise in making strokes.

Having thus described my invention, what I claim as new and desire to secure by Letters Patent, is:

1. A device of the character stated comprising a base having an elevated open-top, forward portion and a rear portion, a member symbolic of a golf ball pivotally mounted in the opening at the base front said member being formed of strips of relatively yielding material glued together and a spring connecting the bottom of said member and the base rear for normally maintaining said member in a vertical position with the major portion thereof projected above said elevated base part.

2. A device of the character stated comprising a base having an elevated open-top, forward portion and a rear portion, a mem-

ber symbolic of a golf ball comprised of strips of material secured together by pins passing laterally through said member adjacent its striking surface, said member being pivotally mounted in the opening at the 70 base front and a spring connecting the bottom of said member and the base rear for normally maintaining said member in a vertical position with the major portion thereof projected above said elevated base part. 75

3. A device of the character stated comprising a base having an elevated open-top, forward portion and a closed, inclined rear portion, a member symbolic of a golf ball pivotally mounted in the opening at the base 80 front said member being formed of strips of relatively yielding material glued together and a spring connecting the bottom of said member and the base rear for normally maintaining said member in a vertical position with the major portion thereof projected above said elevated base part. 85

4. A device of the character stated comprising a base having an elevated, open-top, forward portion and a closed, inclined rear 90 portion, the said opening being elongated and longitudinally disposed and the underside of the inclined portion being slotted longitudinally, a member symbolic of a golf ball comprised of vertically disposed strips 95 secured together laterally considered, a pivot pin passing through said member and journaled in the forward walls of the base opening and a spring connecting the bottom of said member with said base and accommodated in the base slot.

5. A device of the character stated comprising a base having an elevated, open-top, forward portion and a closed, inclined rear portion, the said opening being elongated 105 and longitudinally disposed and the underside of the inclined portion being slotted longitudinally, a member symbolic of a golf ball comprised of vertically disposed strips secured together laterally considered, a 110 pivot pin passing through said member and journaled in the forward walls of the base opening and a spring connecting the bottom of said member with said base and accommodated in the base slot for maintaining 115 said member in a normal vertical position, and means at the base front for limiting forward movement of said member about its pivot point.

6. A device of the character stated comprising a base having an elevated open-top, forward portion and a closed, inclined rear portion, a member symbolic of a golf ball pivotally mounted in the opening at the base front said member comprising a plurality 120 of vertical strips of relatively yielding material glued together and a spring connecting the bottom of said member and the base rear for normally maintaining said member 125 in a vertical position with the major portion 130

thereof projected above said elevated base part.

7. A device of the character stated comprising a base having an elevated open-top, forward portion and a rear portion, a member symbolic of a golf ball pivotally mounted in the opening at the base front said member being formed of strips of relatively yielding material glued together, a metal part for said member substantially oppo-

site its striking face, a link connected to said metal part and projected through said members and a spring connecting said link and the base rear for normally maintaining said member in a vertical position with the major portion thereof projected above said elevated base part.

In testimony whereof, I have hereunto signed my name.

WM. A. F. MACCALLUM.
